[57] CLAIM

The ornamental design for a desk/wall mounted transceiver, as shown and described.

DESCRIPTION

FIG. 1 is a front, top and right side perspective view of a desk/wall mounted transceiver showing our new design;

FIG. 2 is a bottom plan view thereof;

FIG. 3 is a rear elevational view thereof; and,

FIG. 4 is a left side elevational view thereof.

The broken line showings in FIG. 3 are for illustrative purposes only and form no part of the claimed design.
